UNITED STATES PATENT OFFICE.

MARCUS S. WOODS, OF CHATTANOOGA, TENNESSEE, ASSIGNOR TO THE GOOD GRAPE COMPANY, OF CHATTANOOGA, TENNESSEE, A CORPORATION OF TENNESSEE.

DESIGN FOR A BOTTLE.

Application filed October 23, 1924. Serial No. 11,159. Term of patent 14 years.

To all whom it may concern:

Be it known that I, MARCUS S. Woods, a citizen of the United States, residing at Chattanooga, in the county of Hamilton and State of Tennessee, have invented a new, original, and ornamental Design for Bottles, of which the following is a specification.

Referring to the drawing:

The figure is a side elevation of a bottle showing my new design.

I claim:

The ornamental design for a bottle, substantially as shown.

In testimony that I claim the foregoing as my own, I have hereto affixed my signature.

MARCUS S. WOODS.
